UNITED STATES PATENT OFFICE.

WILLIAM H. MINER, OF CHICAGO, ILLINOIS, ASSIGNOR TO W. H. MINER COMPANY, OF CHICAGO, ILLINOIS, A CORPORATION OF ILLINOIS.

BOLSTER FOR CARS OR OTHER VEHICLES.

No. 926,482.

Specification of Letters Patent. Patented June 29, 1909.

Application filed March 28, 1908, Serial No. 423,206. Renewed April 12, 1909. Serial No. 489,626.

To all whom it may concern:

Be it known that I, WILLIAM H. MINER, a citizen of the United States, residing in Chicago, in the county of Cook and State of Illinois, have invented a new and useful Improvement in Bolsters for Cars or other Vehicles, of which the following is a specification.

My invention relates to bolsters for cars or other vehicles, and especially to those of a truss construction, comprising a compression member and a tension member and an intervening strut.

Heretofore, the bolsters of the kind or class to which my invention relates, have ordinarily had the ends of the flat rolled steel tension member folded over the ends of the compression members; and in order to secure the parts together under the proper tension so as to prevent bending or bowing of the compression member, it has been necessary to employ an expensive and special construction of machine by means of which the ends of the flat steel tension member could be folded over the ends of the compression member, while the tension member is heated to a high temperature in order that the subsequent shrinkage of the metal may give the parts their requisite or close tension, fit with each other. And in case of breakage or other serious injury to either the compression member or tension member or other part, it has heretofore been necessary to send the bolster back to the factory where it was made, or where the special machine for uniting the compression and tension members is located, thus rendering repairs extremely difficult, troublesome and expensive, and frequently causing much car and traffic delay.

The object of my invention is to provide an improved construction of trussed rolled steel bolster, by means of which these difficulties may be overcome, and the repairing of the bolster by substitution of a new compression member or new tension member, a new central strut or other part enabled to be made at any ordinary railway car shop, and by which, at the same time, the bolster will be made of an extremely strong and durable construction.

My invention consists in the means I employ to practically accomplish this object or result as herein shown and described.

In the accompanying drawing forming a part of this specification, Figure 1 is a central

vertical sectional view of a car truck bolster embodying my invention. Fig. 2 is a plan view. Fig. 3 is a detail perspective view of one of the angle connecting blocks which connect the compression and tension members, and at the same time afford a horizontal seat for the spring cap. Figs. 4 and 5 are detail views illustrating modifications.

In the drawing, A represents a portion of a car truck frame, B the compression member of the bolster, C the tension member thereof, D one of the angle connecting blocks, E the central strut through which the king bolt extends, F the bolster springs, G the lower spring seat and H the spring cap or follower between the springs and the bolster.

The compression member B may be of any suitable form. It is, however, preferably a channel bar of rolled steel, as illustrated in the drawing. The tension member C is preferably a flat bar of rolled steel, and it is made materially shorter than the rolled steel tension members heretofore in use. The tension member C is furnished at its ends with gibs or shoulders C'.

Each of the angle blocks D is provided with a flat inclined seat or portion d adapted to receive and fit flat against the upwardly inclined end b of the compression member B, and also with a shoulder d' against which the extreme end b' of the compression member B directly and snugly abuts. The end b of the compression member is securely, firmly and rigidly secured to the seat portion d of the angle block D by rivets b'. The angle connecting block D is also provided with an inwardly extending shank portion d' furnished with upright strengthening ribs d'' on the upper side, and provided at its extreme end with transverse shoulders d' and transverse recess d'' to receive the gib or shoulder C' of the tension member C. The shank d' is firmly and rigidly secured to the tension member C by rivets c, the interengaging gibs or shoulders on the tension member and connecting block serving in part to relieve the rivets from shearing strain.

The angle block D is also provided on its lower side with a horizontal cap seat d'' to receive the horizontal cap or bearing plate H of the springs F. The cap seat d'' is preferably surrounded by a marginal flange d''' to embrace the edges of the cap H.

By this improved construction, either the compression member, tension member, the

central strut or either or both of the angular connecting blocks D may be readily and conveniently replaced or repaired without the necessity of any special machine.

5. In the modification illustrated in Fig. 4, the gib or shoulder on the end of the tension member C is on the lower face thereof instead of on the upper. In the modification illustrated in Fig. 5, the tension member C is 10 furnished with a gib or shoulder C' on the face thereof, and in this modification the shank portion of the angular connecting block is made with upper and lower members through which the rivets extend, thus 15 giving a double shear on the rivets.

I claim:

1. In a bolster, the combination with a compression member, of a tension member having gibs or shoulders at its ends, a central 20 strut and a pair of angle connecting blocks, one at each end of the bolster and secured to said compression and tension members, and provided at their shank portions with gibs or shoulders interlocking with the gibs or shoul- 25 ders on the tension member, substantially as specified.

2. In a bolster, the combination with a compression member, and a central strut, of a tension member and an angle connecting 30 block having a shank secured to the tension member, and provided with a flat seat secured to the compression member, and furnished at its under side with a horizontal seat for a spring cap, the shank of said connecting block 35 having a gib or shoulder at its end, and the ten-

sion member having an interengaging gib or shoulder at its end, substantially as specified.

3. In a bolster, a combined connecting and cap seat block D having an inclined flat seat d to receive the inclined end of a compression member, a shank d² furnished with shoulders d³, a recess d⁴ for connection with the end of a tension member and provided with a horizontal seat d⁵ to receive the cap or bearing plate of the springs, substantially as specified. 40

4. In a bolster, a combined connecting and cap seat block D having an inclined flat seat d to receive the inclined end of a compression member, a shank d² furnished with shoulders d³ and a recess d⁴ for connection with the end of a tension member and provided with a horizontal seat d⁵ to receive the cap or bearing plate of the springs, and also provided with a shoulder d⁶ for the extreme end of the compression member to abut against, substantially as specified. 50

5. In a bolster, a combined connecting and cap seat block D having an inclined flat seat to receive the inclined end of a compression member and a shank d² for connection with the end of the tension member and provided with a shoulder to engage the gib or shoulder on the tension member, substantially as specified. 55
